US00D578963S

(12) **United States Design Patent**
Shen et al.

(10) **Patent No.:** US D578,963 S
(45) **Date of Patent:** ** Oct. 21, 2008

(54) **I/O CONNECTOR**

(75) Inventors: **Li Li Shen**, Tu-Cheng (TW); **Hong Tu Zhang**, Tu-Cheng (TW)

(73) Assignee: **Cheng Uei Precision Industry Co., Ltd.**, Taipei Hsien (TW)

(**) Term: **14 Years**

(21) Appl. No.: **29/287,365**

(22) Filed: **Jul. 30, 2007**

(51) **LOC (8) Cl.** 13-03

(52) **U.S. Cl.** D13/133

(58) **Field of Classification Search** D13/133, D13/146, 147, 154, 184, 199; 439/108, 352, 439/354, 357, 358, 374, 567, 607, 608, 609, 439/610, 656, 676, 680

See application file for complete search history.

(57) **CLAIM**

The ornamental design for an I/O connector, as shown and described.

DESCRIPTION

FIG. 1 is a perspective view of an I/O connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the I/O connector showing our new design.

The broken line of the internal elements of the connector in FIG. 3 is included to show unclaimed subject matter only and forms no part of the claimed design.

1 Claim, 8 Drawing Sheets

FIG. 1

FIG. 2

FIG. 3

FIG. 4

FIG. 5

FIG. 6

FIG. 7

FIG. 8
